(57) **CLAIM**

The ornamental design for a bottle and cap, as shown and described.

DESCRIPTION

FIG. 1 is a perspective view showing my new design; FIG. 2 is a front elevational view thereof, the rear elevational view being identical, except for the unclaimed environment; and,

FIG. 3 is a top plan view thereof.

The bottom is flat and devoid of surface ornamentation. The broken lines shown in the drawings are for illustrative purposes only and form no part of the claimed design. For clarity of illustration, the helical pattern shown on the sidewall in FIGS. 1 and 2 has not been shown on the opposing sidewall as would be seen through the transparent surface. However, the helical line pattern is continuous around the sidewall.
